UNITED STATES PATENT OFFICE.

THOMAS J. MURPHY, OF ROCHESTER, NEW YORK, ASSIGNOR OF ONE-HALF TO JAMES P. B. DUFFY, OF ROCHESTER, NEW YORK.

ARC-LAMP SYSTEM.

1,350,170.

Specification of Letters Patent. Patented Aug. 17, 1920.

Application filed January 12, 1917. Serial No. 141,990.

To all whom it may concern:

Be it known that I, THOMAS J. MURPHY, a subject of the King of Great Britain, and a resident of Rochester, in the county of Monroe and State of New York, have invented certain new and useful Arc-Lamp Systems; and I do hereby declare the following to be a full, clear, and exact description of the invention, such as will enable others skilled 5 in the art to which it appertains to make and use the same, reference being had to the accompanying drawings, and to the characters of reference marked thereon, which form a part of this specification.

15 My invention relates to arc lamp systems. It particularly has for its object to provide a system for starting arcs in lamps having tungsten terminals located in a neutral gas at practically atmospheric pressure. 20 The invention may be contained in different arrangements of systems, all of which come within the purview of my claims hereinafter appended. To show the practicality of my invention I have selected one of 25 such systems as an example and shall describe it hereinafter. The system selected is illustrated in the accompanying drawing.

The drawing illustrates a tungsten lamp and a system for controlling and operating 30 the same.

1 is the lamp, which is provided with two balls 2 which are disposed in proximity to each other but are removed from each other sufficient to produce the desired arc between 35 them. They are supported by wires or filaments 3 within the bulb 4. The bulb 4 is filled with an inert gas, such as nitrogen or argon.

The lamp 1 is connected with a system for 40 starting the arc and controlling the flow of the current to and through the lamp when once the arc is started. The lamp is operated by an alternating current, the source of which is connected to the lines 5, 6. One 45 terminal 2 of the lamp is connected through the inductance device 8, while the other terminal 2 of the lamp is connected to a means for starting the arc of the lamp as well as through the inductance device 8 and to the 50 line 5.

A resistance 10 is connected to the line 6 and to a switch 11 which may be operated in one direction by means of a spring 12 to open the circuit from the line 6 through the resistance 10. The resistance 10 operates to

prevent a too great current flow when the switch 11 is closed. The switch contact 13 is connected to the primary 14, which in turn is connected to the resistance 15. The circuit of the resistance 10, primary 14 and 60 resistance 15 is completed by a switch 16 when the switch arm is in contact with the fixed contact 17 to which the resistance 15 is connected.

In starting the lamp the switch 11 is closed 65 and the current passes through the resistance 10, the switch 11 and part of the primary coil 14, to the line 5. This produces a high potential current in the secondary 20, which is connected to the condenser 21 70 through the induction devices 22. The discharge of the condenser is through the lamp 1, the terminals 2 being connected with the terminals of the condenser. The discharge across the terminals 2 is regulated by the 75 adjustable terminals 23. At the same time that the switch 11 is closed to the contact 13, the switch 16 is closed to the contact 17, and when a spark is formed across the terminals 2 an arc is established by the current which 80 passes from the line 6 through the inductance device 8 to the lamp 1, thence through the inductance device 8 to the switch 16 and the resistance 15, and a part of the primary 14 to the line 5, which causes the current to 85 flow through the arc, which current has a potential higher than that of the main lines 5 and 6 by reason of the operation of the booster coil or auto transformer 14. The current having the higher potential is allowed to flow until the terminals are sufficiently heated or until the arc is well established, whereupon the switches 11 and 16 are allowed to move from the contacts 13 and 17, the switch 16 completing the circuit 90 95 directly to the line 5. The current then continues to flow from the main line 6 through the inductance device to the lamp 1, thence through the inductance device 8 and switch 16, directly to the line 5.

I claim:

1. In a lamp lighting system, a source of current supply, a lamp connected to the said source, a primary of a transformer connected at a midpoint with one terminal of the 105 source, means for connecting the other terminal of the source with one terminal of the coil, means for connecting one terminal of the lamp with the other terminal of the coil and disconnecting the last named terminal 110

of the lamp from the said source, the secondary of the transformer connected with the terminals of the lamp.

2. In a lamp lighting system, a source of current supply having a high electro-motive force, and a source of current supply having a lower electro-motive force, a lamp having electrodes connected to the said sources, a third source of current supply having an electro-motive force less than the second named source, means for disconnecting the lamp from the first two named sources of current and connecting it with the third named source.

15 3. In a lamp lighting system, a source of supply having a high electro-motive force, a lamp having electrodes connected to the source, means for causing a disruptive discharge of the current from the said source across the terminals of the lamp, a second source of current connected to the lamp and

having a lower electro-motive force, a third source of current having an electro-motive force lower than the second source, means for disconnecting the lamp from the first 25 two named sources and connecting it with the third source.

4. In a lamp lighting system, a source of current supply having a high electro-motive force and exceedingly small amperage, a second source of current having a lower electro-motive force and larger current, a lamp having electrodes connected to the said sources, a third source of current having an electro-motive force lower than the second 35 named source, means for disconnecting the lamp from the first named two sources and connecting it with the last named source.

In testimony whereof I have hereunto signed my name to this specification.

THOMAS J. MURPHY.
